UNITED STATES PATENT OFFICE.

ROBERT B. PUCKETT AND HARRY R. ABBOTT, OF ST. LOUIS, MISSOURI.

METHOD OF MANUFACTURING TENONED HEELS.

1,253,279.

Specification of Letters Patent. Patented Jan. 15, 1918.

Application filed May 1, 1916. Serial No. 94,560.

To all whom it may concern:

Be it known that we, ROBERT B. PUCKETT and HARRY R. ABBOTT, citizens of the United States, residing in the city of St. Louis and State of Missouri, have invented new and useful Improvements in Methods of Manufacturing Tenoned Heels, of which the following is a specification.

This invention relates to a novel method 10 of manufacturing tenoned heels, and has special reference to a procedure whereby a tenon of the material of which the heel is composed is formed on the seat of the heel during the act of compressing the latter.

In companion applications filed April 17th and April 27, 1916, and serial numbered 91,472 and 93,893, respectively, we have disclosed a method and apparatus for removing a lift from the heel-seat portion of an outer sole. In using soles having an opening formed in their heel-seat portion by removing a lift therefrom it is necessary to fill up this opening either before or at the time of applying the heel to the sole; and in still 20 another application, Ser. No. 71,618, filed January 12th, 1916, we have suggested for this purpose securing to the heel a filling tenon of a material cheaper than the material of which the heel was composed, so that 25 when the heel was applied to the sole the tenon would fill the opening therein made by removing the lift. We have found, however, that the tenon for this purpose can be easily and economically formed in the heel 30 through the act of compressing the latter by simply forming a recess in the upper die or plunger of substantially the size and shape of the lift cut from the sole, so that upon compression a portion of the heel will 35 be received into this recess and not be compressed, or only slightly so, while the remainder of the heel surrounding the portion embraced within said recess will be pressed a considerable distance below the upper surface of the portion within said recess, thereby providing the desired tenon on the heel.

In order that our method may be clearly understood we have illustrated certain stages thereof in the accompanying drawing, in which—

Figure 1 illustrates, partly in side elevation and partly in section, a heel in the condition in which it appears before being placed in the compress;

Fig. 2 is a plan view of the same;

Fig. 3 is a sectional view of the mold and

plunger portion of a compress showing the heel under compression and the tenon being formed therein;

Fig. 4 is a cross sectional view of the heel after being compressed to form a tenon thereon;

Fig. 5 is a view in front elevation thereof; and

Fig. 6 is a plan view of the same.

Referring now to the drawing, the numeral 1 indicates a heel made by building up lifts in the usual way, and which preferably has its upper portion adjacent to the breast 2 of the heel gouged out, as indicated 70 at 3. The heel as thus constructed is then placed in the mold 4 of a compress where it is subjected to pressure in the usual way by a plunger head 5 moving upward in the mold and a die 6 moving downward therein. 75 In order to provide a tenon on the upper side of the heel, however, we provide a recess 7 in the face of the die 6, which recess is substantially of the shape and depth of the lift which has been cut from the heel-seat portion 80 of the outer sole. The leather used for outer soles is sufficiently uniform in thickness to render any variation in thickness between the height of the tenon to be formed by the recess 7 and the thickness of the outer 85 sole, the opening in which is to be filled by the tenon, of no moment. By an inspection of Fig. 3 it will be understood that as the die 6 descends in the mold the portion 8 thereof surrounding the recess 7 will compress the portion of the heel directly under it, while the remaining portion of the heel will enter the recess 7 and thus leave an 90 standing portion or tenon 9 on the upper side of the heel. The depth of the recess 7, 95 however, is such as to permit of compression action on the tenon 9 after the recess 7 has been filled so that the central portion of the heel may not remain uncompressed. Preferably the curved sides of the recess 7 are rounded, as indicated at 10, to permit 100 the ready separation of the tenon 9 from the recess 7 when the die 6 and plunger head 5 are separated. The manner of operating these latter members so as to cause them to

first compress the heel and then to raise the heel out of the mold, and finally to separate so that the heel may be removed, is well known to those skilled in the art, and need not be described or illustrated. After 110 the heel has been compressed as described, it will have the appearance in longitudinal

section illustrated in Fig. 4, in front elevation illustrated in Fig. 5, and in plan illustrated in Fig. 6, that is to say, the tenon 9 will project upwardly from a central part 5 of the heel and the surface of said heel surrounding the tenon will be inclined downwardly from the rounded edges of the heel to the base of said tenon, as indicated at 11, and on the remaining or breast side of the 10 heel the usual curved recess 12, corresponding to the gouged-out portion 2, will appear, such configuration of the upper side of the heel being formed by correspondingly shaping the die 6, as will be understood.

15 We claim:

1. The herein described method which consists in building a complete heel of substantially uniform thickness throughout, and then forming a tenon on the seat side 20 of the heel by compressing the heel around a prescribed portion of said seat side of the size of the desired tenon whereby the uncompressed portion will project above the plane of the compressed portion.

25 2. The herein described method which

consists in building a complete heel of substantially uniform thickness throughout and then forming a tenon on the seat side of the heel by compressing the same between members one of which, opposite said seat side, 30 is provided with a recess of the size of the tenon desired whereby when placed under compression a portion of the material of the heel will enter said recess in a substantially uncompressed condition to form the tenon. 35

3. The herein described method which consists in building a complete heel of substantially uniform thickness throughout and then forming a tenon on the seat side of said heel by compressing the heel around a prescribed portion of said seat side of the size of the desired tenon and below the plane of such portion, and simultaneously shaping the part of the heel around said portion to cause the same to incline from the rounded 40 edges of the heel to the base of said tenon.

In testimony whereof, we have hereunto set our hands.

ROBERT B. PUCKETT.
HARRY R. ABBOTT.
